US0D1095615S

(12) **United States Design Patent** (10) **Patent No.:** **US D1,095,615 S**
(45) **Date of Patent:** **** Sep. 30, 2025**

(54) **HORIZONTAL AIR PUMP**

(71) Applicant: **Guangzhou Aike Information Technology Co., Ltd., Guangdong (CN)**

(72) Inventor: **Le Wang, Hunan (CN)**

(**) Term: **15 Years**

(21) Appl. No.: **29/986,843**

(22) Filed: **Jan. 18, 2025**

(51) **LOC (15) Cl. 15-02**

(52) **U.S. Cl.**

USPC **D15/7**

CLAIM

The ornamental design for a horizontal air pump, as shown and described.

DESCRIPTION

FIG. 1 is a front, left and bottom perspective view of a horizontal air pump showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the horizontal air pump that form no part of the claimed design.

1 Claim, 8 Drawing Sheets
